UNITED STATES PATENT OFFICE.

IRA E. STUMP, OF CLEVELAND, OHIO.

VALVE AND HORN.

990,923.

Specification of Letters Patent.

Patented May 2, 1911.

Application filed April 8, 1910. Serial No. 554,177.

To all whom it may concern:

Be it known that I, IRA E. STUMP, a citizen of the United States, residing at Cleveland, in the county of Cuyahoga and State 5 of Ohio, have invented certain new and useful Improvements in Valves and Horns, of which the following is a specification.

My invention relates to improvements in valves and horns, and more particularly to 10 a combined "cut-out" valve and signal horn, being designed for use in connection with the exhaust-pipe leading from a hydrocarbon or explosive engine to the muffler commonly employed with automobiles. Under 15 ordinary circumstances when the exhaust is forced directly to the muffler, there is considerable back-pressure resulting in a certain loss of power by impeding the action of the motor, consequently, what are known as

20 "cut-out" valves, are frequently provided whereby the exhaust may be permitted to escape directly through the valve and into the air instead of through the muffler. In exhaust valves and horns of this class, there 25 is a tendency of the parts and ports to become covered and clogged with carbon in the form of soot by the action of the exhaust gases, and the primary object of this invention is to provide a generally improved combined "cut-out" valve and signal horn of 30 this class, of simple, cheap, and efficient construction, in which the several parts are so disposed, constructed, and arranged as to reduce the above mentioned tendency to a 35 minimum.

A further object of the invention is to provide a valve of this class capable of receiving the exhaust from explosive engines and distributing the same either to the muffler 40 or to another point of discharge without producing an undue accumulation of back-pressure. This point of discharge may be directly to the atmosphere through the "cut-out" valve, or indirectly thereto through 45 the horn portion of the valve body above referred to.

With the above mentioned and other objects in view, the invention consists in the novel construction, arrangement, and combination of parts, hereinafter described, 50 illustrated in one of its embodiments in the accompanying drawings, and particularly pointed out in the appended claims.

Referring to the drawings forming a part 55 of this specification, Figure 1, is a top plan view of the improved exhaust valve and

signal horn, the horn valve being in its operative position for diverting the operating fluid or exhaust gases to the horn or whistle slot opening for sounding the horn in a well known manner. Fig. 2, a side elevation of same with removable head of the valve body or casing removed. Fig. 3, a longitudinal sectional view of the same. Fig. 4, a side elevation of same, showing the horn valve 60 shifted out of its operative position and allowing the exhaust gases or operating fluid to pass unobstructed to the muffler, a portion of its walls being broken away for clearer illustration of the parts. Fig. 5, a 65 detail perspective view of the horn valve removed from the valve casing.

Similar numerals of reference designate like parts throughout all the figures of the drawings.

The improved valve and horn comprises a valve body or casing 1, (preferably of cylindrical form as shown) and provided with oppositely arranged and extending branches 2, and 3, to receive and contain the inlet and 70 outlet branches 4, and 5, of the exhaust pipe, the outlet branch 5, thereof being adapted to lead to a muffler when the exhaust is from an explosive engine.

The valve body or casing is provided at 75 one side and intermediate the branches 2, and 3, with a cut-out port-opening 6, and at the other with a horn or whistle slot 7. The port-opening 6, is preferably beveled as shown, and is normally closed by means of a valve-head 8, provided with beveled or flaring sides 8^a, adapted to be seated upon the correspondingly beveled edges of the cut-out opening 6. As a means for opening and closing the port-opening 6, the valve-head 90 is mounted upon and carried by an operating lever 9, mounted outside of the valve body and, in the present instance, pivotally secured thereto by means of a bearing-arm or standard 10. The valve-head 8, is normally held in its closed position by means of a spring 11, in the present instance, secured to the bearing-arm or standard 10. When it is desired to discharge the exhaust gas directly into the atmosphere or to relieve 100 any undue back-pressure resulting from the exhaust being forced directly to the muffler, the valve-head 8, is adapted to be lifted or opened by means of suitable connections or operating means connected to the free end 105 9^a, of the lever 9.

As a means for diverting the operating

- fluid or exhaust gases to the whistle-slot 7, a horn valve is mounted within the valve body or casing 1, by means of a rock or pivot shaft 11^b, said horn valve comprising 5 a hub portion 11^c, and a supporting disk portion 12, carrying a curved valve-head 13. The curved valve-head 13, is adapted to conform to the contour of the inner periphery of the valve body or casing, and is of such 10 size that when moved to the position shown in Figs. 1, and 2, of the drawings, it is adapted to cover the inlet branch 4, of the exhaust pipe. One edge of the valve-head 13, is provided with a beveled or shear cutting edge 13^a, adapted to clear the inner walls of the valve body or casing from any 15 accumulating carbon when moved within said casing by the means hereinafter described.
- 20 As a means for providing a passage for the escape of the operating-fluid to the whistle slot 7, when the valve-head is in its operative or fluid diverting position the front portion of the valve-head is preferably provided with a depressed or undercut portion 13^b, in its outer periphery so that a corresponding passage or recess will be formed for the escape of the operating fluid to the whistle slot 7, as indicated most clearly in 25 Fig. 2, of the drawings. The bearing or pivot shaft 11^b, is mounted in suitable bearing openings in an integral head 14, and a removable head 15, of the valve body or casing 1. A lever bar 16, is adjustably mounted 30 in the projecting end of the pivot shaft 11^b, by means of a screw 17, and the lever bar 16, may be operated by means of a cord or cable 18, leading to a foot-lever or other operating mechanism (not shown) in the 35 body of the vehicle. As a means for returning the valve-head 13, to its initial position shown in Fig. 4, of the drawings, the lever- 40
- bar 16, may be provided with a spring 19, suitably connected whereby the lever-bar 16, will be moved against the resistance of said 45 spring. As a means for limiting the movements of the lever-bar 16, and stopping the valve-head 13, in its proper positions when reciprocated, stop-lugs or pins 20, may be formed integral with the head 14, of the 50 valve casing as shown.
- Having thus described my invention, what I claim and desire to secure by Letters Patent is,—
1. A valve and horn, comprising a valve body provided with inlet and outlet branches and a whistle slot intermediate said branches, and a rotary valve mounted within said valve body and adapted to be carried in front of said inlet branch, said valve being provided at its periphery with a recessed portion forming a passage for diverting the exhaust gases from said inlet branch to said whistle slot when moved in front of said inlet branch. 55
  2. In a valve and horn, the combination with an exhaust pipe, and a valve body connected thereto and provided with a whistle-slot intermediate the inlet and outlet branches of said exhaust-pipe; of a rotary valve-head mounted within said valve body and adapted to be carried in front of said inlet branch, said valve-head being provided on its periphery with a recessed portion forming a passage for diverting the exhaust 60 gases from said inlet branch to said whistle-slot. 75

In testimony whereof I have affixed my signature, in presence of two witnesses.

IRA E. STUMP.
